UNITED STATES PATENT OFFICE.

BUEL S. BURROUGHS, OF KINGSTON, NEW YORK.

WINDOW-VENTILATOR.

No. 806,105.

Specification of Letters Patent.

Patented Dec. 5, 1905.

Application filed January 18, 1905. Serial No. 241,666.

To all whom it may concern:

Be it known that I, BUEL S. BURROUGHS, a citizen of the United States, residing at Kingston, in the county of Ulster and State of New York, have invented certain new and useful Improvements in Window - Ventilators, of which the following is a specification, reference being had therein to the accompanying drawings, which form a part thereof.

10 My invention relates to window-ventilators, and more particularly to that class thereof adapted to prevent condensation upon the window pane or plate in addition to providing a circulation of pure air within a window-15 seat, room, or other apartment.

The main object of the invention is to provide means of ventilation adjacent to a window-pane to prevent the accumulation of moisture and frost thereon due to the warm air 20 within a window-seat, room, or apartment contacting with the chilled surface of the window pane or plate.

A further object is to provide means whereby water from the inside of the window pane 25 or plate, whether such result from condensation thereon or from the cleaning of the window, will be collected and carried to the outside of the window-sash, thus avoiding the presence of water within the window-seat, 30 room, or apartment.

A still further object is to provide means whereby the lower bar of the window-sash will be protected from the ravages of this water, as well as of the weather, so as to avoid 35 premature decay thereof and the resulting danger due to a loosening of the pane or plate relative thereto.

A still further object is to provide means whereby the quantity of air placed in circulation through the ventilator may be conveniently regulated from within the apartment, and a still further object is to provide a device of this character which will be simple in construction, which will facilitate the mounting of the pane in the sash, which will be weatherproof, and which will be inexpensive to manufacture.

The invention consists in the novel features of construction and arrangement of parts 50 hereinafter set forth and described, and more particularly pointed out in the claims hereto appended.

Referring to the drawings, Figure 1 is a view of the top and of the bottom of the exterior of a window-front embodying my invention. Fig. 2 is a vertical section thereof.

Fig. 3 is a detail view in perspective of the pane-support and ventilator, and Fig. 4 is a similar view of the pane or plate cap and ventilator.

60

Like letters refer to like parts throughout the several views.

The accompanying illustrations show the invention as applied to a display-front, in which—

65

a denotes the window-sash, the top and side bars of which are provided with the usual strips *b b'* for holding the pane or plate therein.

Secured upon the bottom bar of the sash *a* in any desired manner I provide a pane or plate support and ventilator which holds the lower edge of the pane or plate, thus dispensing with the bottom sash-strips ordinarily employed for this purpose. This support and ventilator comprises a base *c*, adapted to rest 70 upon and be attached or secured to the lower bar of the window-sash, as by the fillet *d*, entering a channel *b'* in said bar. Approximately centrally of said base is a laterally-extending vertical web *e*, in which are a plurality 80 of inlet and vent openings *e'*, the lower edges of which are flush with the upper and preferably inclined surface of the base *c*. The part *c'* of the base *c* outside said web projects outwardly, so as to act as a shield for and to 85 carry away water over the lower bar of the window-sash, and that part *c'* thereof within the web curves upwardly into a laterally-extended flange *f*, forming, with said web, a gutter *f'*, adjoining the pane or plate. The web 90 *e* is surmounted by a head *g*, having parallel side flanges *g' g'*, forming a channel *g''* in the upper face thereof adapted to receive and retain the lower edge of the pane or plate.

Mounted in oppositely-disposed parallel 95 ways *h h'* in the base *c* and the head *g*, respectively, is a slide *i*, having therein a plurality of openings *i'*, adapted to register with the air-inlet openings *e'*, by means of which the size of said openings *e'* and the quantity of 100 air passing therethrough may be regulated. An arm *j*, moving in the gutter *f'* and having a bearing *j'*, conforming to and adapted to move upon the top of the flange *f*, is carried by said slide, which slide is controlled thereby, a knob *j''* being provided on said arm for the convenient operation of said slide.

The top of each flange *g'* of the head *g* is beveled downwardly and away from the channel *g''* in said head, so as to avoid an accumulation of water thereon adjoining the pane or plate.

105

110

To insure a circulation of air within the window-seat, room, or apartment, I provide, in combination with the parts heretofore referred to, a cap and ventilator for the top edge 5 of the pane or plate, which also serves to hold the top of the pane or plate with relation to the sash. This cap comprises a head k , adapted to pass between and be held by the top strips $b b'$, a web l , having a plurality of vent-openings l' therein, and a base m , presenting downwardly oppositely disposed parallel flanges m' , forming a channel m^2 , adapted to receive the top of the pane or plate, and thus serve to retain same relative to the top bar of the window-sash. A slide n , movable in parallel ways $o o'$ in the head k and base m , respectively, having a plurality of openings n' therein adapted to register with the vent-openings l' in the web l , and a controlling-knob p , are provided 15 to regulate the size of the openings l' and the quantity of air passing therethrough.

The bottom support and ventilator and also the cap and ventilator are preferably cast of iron or other metal in a single piece and of a 25 width of approximately one-half an inch wider than the standard widths of lights to provide the proper clearance on the sides corresponding with that ordinarily allowed in window-sashes, and the slides i and n are preferably 30 cast in brass.

To obviate the difficulties arising from superficial inaccuracies and inequalities of the channel g^2 due to the imperfections resulting from casting, I place in said channel a rubber or other similar or suitable packing-strip g^3 , which in addition to this function renders the lower edge of the pane or plate weatherproof.

In the application of my invention to a window the top edge of the pane or plate, as r , is first inserted between the flanges $m' m'$, so as to retain said cap upon said pane or plate, and the lower edge of said pane or plate is placed between the flanges $g' g'$ of the support and ventilator. The sides, the top bar, and the bottom bar and the ends of the side strips adjacent thereto of the sash having been prepared to receive, respectively, the side edges of the pane or plate, the head k , 45 and the support or ventilator, the entire pane or plate and the bottom support, with the cap therewith, is raised into position relative to the sash, the head k of the top cap passing between the two top strips $b b'$ to an extent to permit the fillet d to pass over the bottom bar and enter the channel b^2 . The side strips are then secured to the sash. In storefronts or similar relations, where the weight and size of the light make it difficult to handle, straps may readily be placed through the inlet or vent openings e' , thus serving to hold the support and the pane or plate together while mounting them in the sash and also facilitating such mounting. It will be 55 observed that inasmuch as the said strap

would not at any time be between the support and the lower bar of the sash it can readily be removed after such mounting.

The mode of operation of the herein-described structure is apparent from the foregoing description. Air in any desired quantities may be admitted through the inlet or vent openings e' by moving the slide i so as to regulate the size of said openings. The gutter f' will divert said air so as to bring it close to the pane, thus avoiding direct drafts. The heated air within the window-seat, room, or other apartment will rise and pass therefrom through the vent openings l' in quantities largely controlled by the regulating-slide 75 n . The circulation of air thus produced will so equalize the temperature of both sides of the pane or plate as to avoid the condensation of the heated air thereon and in cold weather the accumulation of frost. Any water from 80 the pane or plate will be collected in the gutter f' and will drain through the inlet or vent openings e' over the shield c' , thus protecting the bottom bar of the window-sash and avoiding that premature decay noticeable especially 85 in store-fronts. It will also be observed that the extended base c holds the pane or plate and that any loosening of the pane or plate could occur only through the disarrangement 90 of the entire support through a partial or 95 complete destruction of the entire bottom bar of the sash.

The height of the side flanges $m' g'$ should be such relative to the space above the head k as to prevent such a vertical movement of 100 the cap either alone or together with the pane or plate as would permit the said cap to be removed from the top edge of the pane or plate or to permit the pane or plate to be removed from the channel g^2 . The side strips, 105 in conjunction with the fillet d and the channel b^2 , serve to maintain said support and ventilator in relation to the window-sash.

While I have shown and described the invention as applied to a store-front, in which 110 field I conceive it will have its greatest utility, it is apparent that it may be similarly applied in other connections by reducing the dimensions of the various constituent parts to conform to the desired application thereof. Its 115 mode of operation in all such connections will remain substantially unchanged.

By reason of the construction herein described the device is inexpensive to manufacture and the air circulation therethrough may 120 be readily controlled.

It is not my intention to limit the invention to the precise details of construction herein shown and described, such being capable of variation to adapt the invention to various 125 analogous uses.

Having described the invention, what I claim as new, and desire to have protected by Letters Patent, is—

1. In a window-ventilator, the combination 130

with a window-sash, a pane or plate therefor, and sash-strips, of a pane or plate support comprising a base, a flanged head and a web connecting said base and said head and having 5 therein a plurality of openings.

2. In a window-ventilator, the combination with a window-sash, a pane or plate therefor, and sash-strips, of a pane or plate support comprising a base, a flanged head, a web connecting 10 said base and said head and having therein a plurality of openings, and a flange on said base forming with said web a gutter within said support, communicating with said openings.

15 3. In a window-ventilator, the combination with a window-sash, a pane or plate therefor, and sash-strips, of a pane or plate support comprising a base, a flanged head, a web connecting 20 said base and said head and having therein a plurality of openings, and means regulating the size of said openings.

25 4. In a window-ventilator, the combination with a window-sash, a pane or plate therefor, and sash-strips, of a pane or plate support comprising a base, a flanged head, a web connecting 30 said base and said head and having therein a plurality of openings, said head and said base having oppositely-disposed ways adjoining 35 said web, a slide having a plurality of openings therein adapted to register with the openings in said web, and means whereby said slide may be actuated to regulate the size of said openings in said web.

40 5. In a window-ventilator, the combination with a window-sash, a pane or plate therefor, and sash-strips, of a pane or plate support comprising a base, a flanged head, a web connecting 45 said base and said head and having therein a plurality of openings, said base being projected over said sash whereby a shield therefor is provided, and a flange on said base forming with said web a gutter within said support substantially flush with said shield and communicating 50 with said openings.

55 6. In a window-ventilator, the combination with a window-sash, a pane or plate therefor, and sash-strips, of a pane or plate support comprising a base, a flanged head, a web connecting 60 said base and said head and having therein a plurality of openings, said head and said base having oppositely-disposed ways adjoining said web, a slide having a plurality of openings therein adapted to register with the openings in said web, means whereby said slide may be actuated to regulate the size of said openings in said web, said base being projected over said sash whereby a shield therefor is provided, and a flange on said base forming with said web a gutter within said support substantially flush with said shield and communicating 65 with said openings.

7. In a window-ventilator, the combination with a window-sash, a pane or plate therefor, and sash-strips, of a pane or plate support comprising a base, a flanged head, a web con- 70

necting said base and said head and having therein a plurality of openings, said head and said base having oppositely-disposed ways adjoining said web, a slide having a plurality of openings therein adapted to register with the 75 openings in said web, said base being projected over said sash whereby a shield therefor is provided, a flange on said base forming with said web a gutter within said support substantially flush with said shield and communicating with said openings, and an arm on said slide bearing upon said flange whereby said slide may be actuated to regulate the size of the openings in said web.

8. In a window-ventilator, the combination 80 with a window-sash, the lower bar of which has a channel therein, a pane or plate therefor, and sash-strips, of a pane or plate support comprising a base having a fillet on the under side thereof adapted to enter said channel, a flanged head, a web connecting said base and said head and having therein a plurality of openings, said base being projected over said sash whereby a shield therefor is provided, and a flange on said base forming with 85 said web a gutter within said support substantially flush with said shield and communicating with said openings.

9. In a window-ventilator, the combination 90 with a window-sash, a pane or plate therefor, and sash-strips, of a pane or plate support comprising a base, a flanged head, a web connecting 95 said base and said head and having therein a plurality of openings, and a top cap comprising a head adapted to pass between the top sash- 100 strips, a base presenting downwardly oppositely disposed flanges, and a web connecting said head and said base having therein a plurality of openings.

10. In a window-ventilator, the combination 105 with a window-sash, a pane or plate therefor, and sash-strips, of a pane or plate support comprising a base, a flanged head, a web connecting 110 said base and said head and having therein a plurality of openings, means regulating the size of said openings, and a top cap comprising a head adapted to pass between the top sash-strips, a base presenting downwardly oppositely disposed flanges, a web connecting 115 said head and said base having therein a plurality of openings, said base and said head having oppositely-disposed ways therein adjoining said web, and a slide having a plurality of openings therein adapted to register with the openings in said web whereby the 120 size of said openings in said web may be regulated.

In witness whereof I have hereunto affixed my signature, this 12th day of January, 1905, in the presence of two witnesses.

BUEL S. BURROUGHS.
